UNITED STATES PATENT OFFICE

LOUIS COURTOT, OF PARIS, FRANCE, ASSIGNOR TO AMERICAN RADIATOR COMPANY,
OF NEW YORK, N. Y., A CORPORATION OF NEW JERSEY

RADIATOR

Application filed May 26, 1923, Serial No. 641,702, and in France May 30, 1923.

My invention relates to a radiator adapted for hot water or steam heating of rooms, and so arranged as to be constructed with the minimum size and weight while possessing a sufficient strength to support shocks as well as an attractive appearance, it being analogous to a piece of furniture.

In order to comply with these various conditions in a simple and economical manner, the invention consists in the construction of a radiator body having thin walls and wherein the strength and appearance are made subsidiary to the question of light weight and the relation between general size and radiating surface, combined with an outer envelope of a more or less decorative character which serves as a protection against damage as well as to conceal said radiator body, and whereof certain parts, and especially the lateral portions, are constituted by radiator elements having sufficiently thick walls and constructed chiefly with a view of obtaining a suitable strength and an attractive appearance.

With this combination it becomes an easy matter to provide a heating device of greater output and less expensive construction for a given size, than in a device wherein a thin-walled radiator body is covered with a simple envelope or casing whose walls do not produce heat, and in which the construction is always expensive should the device be required to have an ornamental or esthetic character.

The accompanying drawings show by way of example two forms of construction of a radiator according to the invention.

Fig. 1 is an elevation, partly in section, of a radiator adapted for mounting in the middle of a room, and,

Fig. 2 is a side view of the same in section.

Fig. 3 is a plan view of the same radiator partly in section.

Fig. 4 is an elevation of a portion of a modified form of radiator with the front plate omitted,

Fig. 5 is a transverse section of the same; and

Fig. 6 is a plan thereof with the top omitted, parts being in section.

In Figs. 1 to 3, 1 indicates a radiator body

which is shown in a diagrammatic manner and which in principle requires to be protected and concealed. Adjacent the said body 1 are disposed two cast iron radiator elements 2 which are connected with the ends of the body by suitable means and are also cross-connected by rods or braces 3. The two main sides of the body 1 are protected by sheet or cast metal plates 4, 5 secured to corresponding ribs of the elements 2, preferably in a removable manner to provide for cleaning the said main body. The said plates may be plain or apertured, or if required, embossed or stamped or provided with separately attached mouldings or ornaments. The main body is covered by a top cover 6 which is preferably apertured for the outlet of hot air and may be made in one or more pieces. The inlet and outlet pipes for the heating fluid 7 and 8, are secured to one of the elements 2 or to both these elements as desired, either at the side as represented, or at the back of the radiator so as to conceal the piping and valves as much as possible. The said elements may be given any suitable cross-section and may be constructed in any desired manner provided the outer faces have sufficient strength and an appearance such as will be in harmony with the room wherein it is placed.

The form of construction shown in Figs. 4 to 6 is adapted to be mounted against the wall; the plate 5 adjacent the wall is provided with an insulating covering 9 and may be polished at the outer part or provided with a facing which forms a reflector towards the interior of the room whereby radiation towards the wall shall be reduced as much as possible. To obviate the blackening of the wall above the radiator, it is preferable to mount the apertured part of the top cover 6 at some distance from the wall and to dispose above or below said cover a deflecting member 10 which is so inclined as to direct the current of hot air issuing from the top openings towards the centre of the room.

The main body of the radiator 1 is shown in this case as composed of a set of tubular cast iron elements having a small thickness and large radiating surface and secured to

100

gether as in known cast iron radiators, or by like means. The elements 2 which are secured to the end elements of said main body will have thicker walls, if required, and their external faces may be plain or provided with mouldings or like ornamental parts obtained by casting, or may be composed of separate tubes.

5 The plate 4 is secured to the ribs 11 of the elements 2 by suitable locks 1^a or by like means providing for the ready removal of said plate for cleaning purposes, and in this event the elements 2 will extend forwardly of the plate 4 by a certain amount so as to afford the appearance of the uprights of a piece of furniture. The opposite plate 5 may be secured and disposed in the same manner as the preceding, or otherwise.

10 The top cover 6 is secured by screws 12 to the lugs 13 of the elements 2, and to provide for any slightly variable distance between the latter it is advisable in order to facilitate the mounting to render at least one of said lugs adjustable, it being for example constituted by a screw which is screwed into the element 2, the head being provided with a screwthreaded hole adapted to receive the screw 12.

15 In order to increase the output of the apparatus it may be advisable to dispose at the interior and between said tube elements a set of sheet metal plates 14, flat or corrugated, which are attached for example to the plate 5 and become heated by radiation, then heating the air by convection.

20 In the example shown in Figs. 4 to 6, an opening 15 is made at the bottom of the wall for the inlet of cold air, and the lower part of the radiator is provided with a deflector 16 so inclined as to direct the said incoming air to the centre of the room. Obviously, the use of this latter arrangement is optional.

25 The body of said radiator which it is desired to conceal and protect may of course be made of any suitable types of elements such as flat plates, tubes with or without radiating flanges, worm tubes, and the like, which are arranged or grouped in any desired manner.

Claims:

30 1. A radiator comprising in combination a main radiator body having thin walls, a protecting envelope comprising two radiator elements having strong walls and secured to the ends of the said main body, vertical metal plates extending between the two latter elements, and a metal plate serving as a top cover; one of the said vertical plates being insulated at the outer side and adapted to reflect the heat towards the interior of the radiator, substantially as specified.

35 2. A radiator comprising in combination a main radiator body having thin walls, a protecting envelope comprising two radiator elements having strong walls and secured to the ends of the said main body, vertical metal

40 plates extending between the two latter elements, and a metal plate serving as a top cover; said top cover being provided with apertures, and a deflecting device whereby the hot air rising from the radiator is deflected in an inclined direction through the said apertures, for the purpose set forth.

45 3. A radiator comprising in combination a main radiator body having thin walls, a protecting envelope comprising two radiator elements having strong walls and secured to the ends of the said main body, vertical metal plates extending between the two latter elements, and a metal plate serving as a top cover; the said radiator elements having strong walls extending forwardly of one of the said vertical plates to a slight degree, for the purpose set forth.

50 4. A radiator comprising in combination a main radiator body having thin walls, a protecting envelope comprising two radiator elements having strong walls and secured to the ends of the said main body, vertical metal plates extending between the two latter elements, a metal plate serving as a top cover, and means for securing the said top cover to the said elements; said means consisting of horizontal screws engaging said elements and having therein a transverse screwthreaded hole, and vertical screws traversing said top cover plate and engaging the screwthreaded holes in said horizontal screws, substantially as specified.

55 5. A radiator comprising hollow end wall members adapted to receive a circulating heating fluid, intermediate wall members of fixed width engaging said end wall members and serving to maintain said end wall members spaced apart in fixed relation and forming therewith a casing open at its top and bottom, and means disposed within said casing between and communicatively connecting said end wall members; said last mentioned means serving as additional heating surface, substantially as specified.

60 6. A radiator comprising hollow end wall members adapted to receive a circulating heating fluid, and side wall members composed of vertical plates of fixed width interposed between and engaging said end wall members and serving to maintain said end wall members spaced apart in fixed relation to form therewith a vertical enclosure open at its top and bottom, and means for communicatively connecting said end wall members and serving as additional heating surface; said enclosure and said means for connecting the end wall members constituting a radiator of minimum capacity, and a cover member having air outlet means therein disposed upon the upper portion of said enclosure, substantially as specified.

65 7. A radiator comprising closed, hollow end wall members adapted to receive a circulating heating fluid, intermediate side wall

members of fixed width disposed between and engaging said end wall members inwardly of the edges thereof and serving to maintain said end wall members spaced apart in fixed relation and forming therewith a casing constituting a radiator of minimum capacity; said end sections being adapted to receive therebetween additional heating elements, and means for communicatively connecting said additional heating elements with said end wall members and cooperating therewith to form a radiator of greater capacity, substantially as specified.

8. A radiator comprising hollow end wall members adapted to receive a circulating heating fluid, vertical plates disposed between and engaging said end wall members inwardly of the edges thereof and serving to maintain said end wall members spaced apart in fixed relation, and forming therewith an enclosure open at its top and bottom, means communicatively connecting said end wall members and serving as additional heating surface, and a cover member with an outlet therein having a flange extending over said end wall members and said plates, substantially as specified.

9. A radiator comprising hollow end wall members arranged in fixed spaced relation and adapted to receive a circulating fluid, solid side wall members intermediate said end wall members and forming therewith a casing of fixed geometrical outline; said casing constituting a radiator of fixed minimum capacity adapted to receive therein additional heat emitting elements, and means communicatively connecting said end wall members and serving as additional heating surface, whereby to increase the capacity of the radiator to the maximum limit thereof as determined by said fixed geometrical outline, and a cover plate providing air outlet means, said cover plate serving to enclose the upper portions of said casing, substantially as specified.

45 In testimony, that I claim the foregoing as my invention I have signed my name.
LOUIS COURTOT.
